UNITED STATES PATENT OFFICE.

ARTHUR J. CARLSON, OF VERNON, TEXAS.

SLICING DEVICE.

Application filed July 23, 1926. Serial No. 124,450.

This invention relates to an improved device for facilitating slicing of meats and vegetables in a manner to insure a clean cut of the desired thickness.

5 Briefly, the invention has reference to a device of this kind including a downwardly inclined supporting table, a stop at one end of the table against which the part to be cut is rested, a knife guide and abutment at one 10 end of the table, and spring pressed means for maintaining the blade of the knife in engagement with the guide.

15 My principal aim is to provide a simple and inexpensive device capable of being constructed from easily obtainable parts arranged in a novel association to render the structure highly practical, convenient and useful.

20 Other objects and advantages of the invention will become apparent from the following description and drawings.

25 In the accompanying drawings forming a part of this application and in which like numerals are employed to designate like parts throughout the same:

Figure 1 is a top plan view of a device constructed in accordance with the present invention.

30 Figure 2 is an end elevation of the structure shown in Figure 1 looking in a direction from right to left.

Figure 3 is a vertical section taken approximately upon the plane of the line 3—3 of Figure 2.

35 Figure 4 is a fragmentary sectional and elevational view showing the spring means which is associated with the spring pressed guide bar.

40 Figure 5 is a perspective view of one of the details separated from the complementary parts.

45 Referring to the drawings in detail it will be seen that the device comprises a base plate 1, an inclined top 2, a relatively short front wall 3, end walls 4, a compartment 5, and hinged closing doors 6 for the compartment. The base projects beyond one end wall as at 7 and metal strips 8 have their lower ends 9 rigidly fastened thereto as shown plainly in 50 Figure 3. The upstanding portion of the strips are provided adjacent their upper ends with angular brackets 10. The horizontally directed portions of the brackets are connected with the under side of a pressure bar 11. The inner edge of this bar is faced with metal as at 12, and the top is also faced

with metal 13. The metal facing extends beyond one edge of the bar and terminates in an overhanging flange 14 extending over the upper bifurcated ends of the uprights 8. 60 Bolts 15 are connected with these bifurcated ends and fitted into sockets formed in the pressure bar. Coil springs 16 surround the bolts and wing nuts are threaded on the threaded ends of the bolts. The bolts fly 65 freely through the bifurcations.

The top 2 extends beyond one end wall as shown at 18 and the extended portion is reduced to accommodate the metallic guide member 19 shown in Figure 5. One arm 20 70 is fastened to the upper side of the reduced portion, and the other arm 21 is fastened to the lower side. The arm 20 is provided with an upstanding extremity 22 which is fastened to the aforesaid stop 23 on one longitudinal edge of the table. The bight portion 24 which is curved somewhat as shown in Figure 5 extends beyond the opposite edge of the table as indicated in Figure 2 and also Figure 1. Then as represented in Figure 3, the edge portions of the arms 20 and 21 extend beyond the top 2 and a slot is left between these edge portions and the spring pressed pressure bar 11. 75

80 In practice, the object to be cut is placed upon the inclined table top as represented in dotted lines in Figure 2. It may be assumed, as represented here, a side of bacon is to be acted upon. One longitudinal edge is permitted to rest against the upstanding stop 23 and one end is allowed to overhang the slot existing between the knife guide 85 19 and the spring pressed pressure bar 11. Obviously, by firmly holding the bacon in place and inserting the knife at the right hand end of the slot represented in Figure 2, it will be readily guided into place by the projecting bight portion 24. Then it may be drawn downwardly through the slot to sever a slice of the bacon. The spring 100 pressure exerted against the part 11 will serve to hold the knife blade rather rigidly so that the cutting operation may be carried out rather easily.

105 It is believed that by considering the description in connection with the drawings, a clear understanding of the invention will be had. Therefore, a more lengthy description is thought unnecessary.

110 Minor changes coming within the field of invention claimed may be resorted to if desired.

Having thus described the invention, what I claim as new and desire to secure by Letters Patent is:—

1. In a structure of the class described, a table top, a metallic strip at one end of said top, said strip being bent upon itself at a point between its ends to provide upper and lower arms, the upper arm being attached to the upper side of the top and the lower arm to the lower side of said top, the bight portion extending beyond one longitudinal edge of said top, said strip constituting a stationary abutment against which the blade of a knife is adapted to bear during the slicing operation.
2. In a structure of the class described, a table top, a metallic strip at one end of said top, said strip being bent upon itself at a point between its ends to provide upper and lower arms, the upper arm being attached to the upper side of the top and the lower arm to the lower side of said top, the bight portion extending beyond one longitudinal edge of said top, said strip constituting a stationary abutment against which the blade of a knife is adapted to bear during the slicing operation.

tudinal edge of said top, said strip constituting a stationary abutment against which the blade of a knife is adapted to bear during the slicing operation, and a spring pressed member disposed in spaced parallelism to said abutment, whereby to provide a knife blade guide slot.

3. In a structure of the class described, a box open on one side to provide an internal compartment, closures for said open side, the top of the box being inclined and providing a table top for reception of the part to be cut, there being a stop along one longitudinal edge of said top, a stationary metallic abutment secured to one end of said top and projecting beyond it, a spring pressed metal faced pressure bar located in spaced parallelism to said abutment, uprights, and connecting means between the uprights and pressure bar.

In testimony whereof I affix my signature.

ARTHUR J. CARLSON.
